SCRUBBING AND POLISHING APPARATUS

John S. Nachtmann, Youngstown, Ohio

Original application March 30, 1937, Serial No. 133,911. Divided and this application April 3, 1941, Serial No. 386,656

10 Claims. (Cl. 15—77)

The invention relates to apparatus for producing metal stock coated with dissimilar metal, and particularly to scrubbing and polishing apparatus constituting a part of apparatus for continuously coating sheet and the like ferrous metal stock with tin, whereby sheets, strips and the like of indefinite length may be produced continuously in finished marketable form.

This application is a division of my copending application Serial No. 133,911, filed March 30, 1937, patent No. 2,240,265, dated April 25, 1941, and entitled Method of continuously tin plating ferrous metal stock.

The method of tin plating ferrous metal stock which is disclosed in said application Serial No. 133,911 includes steps such as providing a continuous supply of stock by attaching, preferably by welding, the end of a fresh strip to the end of an exhausted strip, adjusting the feed of the strip in such a manner, preferably by means of a looping slack-producer, that continuous passage of the strip through subsequent stages of treatment in the apparatus may be continued during the period when the end of an exhausting strip is held stationary for welding to it the end of a fresh strip, cleaning the stock by passing it through appropriate cleaning and degreasing baths of electrolytic or other appropriate forms, scrubbing the stock by brushing mechanism, rinsing and pickling the stock with subsequent scrubbing, electroplating the stock with subsequent scrubbing, rinsing and drying the stock, alloying, cleaning and burnishing the stock, and finally coiling or otherwise appropriately preparing it for removal and handling.

The apparatus disclosed in said application Serial No. 133,911 is adapted for continuously coating metal stock in strips, wires or sheets of indefinite length, and includes, means for supporting metal stock to be fed into the apparatus, means for joining the end of one piece of stock to another to produce a continuous strip, means providing for stopping the end of the strip during the joining operation, while the balance of the strip continues to move through the apparatus, means for cleaning, pickling, scrubbing, rinsing, plating, drying, alloying and burnishing the stock, and means for properly guiding and tensioning the strip during its travel and in various novel features inherent in the means referred to.

Said apparatus includes novel scrubbing and polishing apparatus for scrubbing the stock after cleaning and degreasing treatment, after rinsing and pickling, and immediately after electro-

plating, and also for burnishing a coated product.

This application relates specifically to said novel scrubbing and polishing apparatus which, although adapted for use in continuously tin plating ferrous stock, is also adapted for scrubbing and polishing ferrous stock coated with other dissimilar metals, as well as for scrubbing and polishing non-ferrous or non-metallic stock.

Prior scrubbing and polishing apparatus has included brush rolls over which a strip or sheet is pulled, but with such apparatus the bristles of the brush rolls are subjected to undue wear and pressure and scratches and stains are formed on the surface of the strip.

In such prior apparatus the strip is pulled over rotating brush rolls in such a way that the strip partially wraps around the brush rolls, and the tension on the strip produces pressure radial to the brush roll axis between the strip and brush roll. This radial pressure causes the bristles of the brush to bend and break with the result that the brushing action is not uniform and scratches and streaks are formed on the brushed surface.

Due to the fact that rolled steel is seldom, if ever, perfectly flat, especially when under tension, the pressure between the brush roll and the strip is uneven, which results in non-uniform brushing action, particularly when the strip vibrates.

The partial wrapping of the strip around the brush rolls forms a concave arcuate surface of the strip contacting the brush, which with the tension on the strip causes a pounding action tending to drive surface stains into the metallic surface of the strip.

According to the present invention, the strip is wrapped slightly around the surface of a solid back up roll for each brush roll, and the pressure between the brush roll and the strip is adjustable independently of the tension on the strip, so that no radial pressure is exerted on the brush roll and a relatively small convex area of the strip is brushed.

Consequently, vibration of the strip is eliminated, buckling and distortion minimized, the life of the brush rolls greatly prolonged, and a uniformly brushed surface free from scratches and stains is produced on the strip.

It is therefore an object of the present invention to provide an improved apparatus for scrubbing and polishing both surfaces of strips or sheets and the like without causing scratches or otherwise marring the surfaces thereof.

Another object is to provide an improved

scrubbing and polishing apparatus having adjustably mounted scrubbing rolls cooperating with vertically aligned back up rolls.

A further object is to provide an improved scrubbing and polishing apparatus having scrubbing rolls arranged to sweep lightly over slightly convex arcuate surfaces of the strip for uniformly scrubbing and polishing the strip.

Another object is to provide improved means for vertically adjusting the brush rolls toward and away from the back up rolls.

A further object is to provide brushing apparatus in which the life of the brush rolls is greatly prolonged.

A still further object is to provide improved means for axially reciprocating the brush rolls laterally of the strip while the rolls are rotating.

These and other objects are accomplished by the parts, improvements, combinations and arrangements comprising the present invention, preferred embodiments of which are shown by way of example in the accompanying drawings, and hereinafter described in detail and defined in the appended claims.

Referring to the drawings forming part hereof,

Figure 1 is a somewhat diagrammatic view in side elevation of a preferred form of scrubbing and polishing apparatus comprising the present invention;

Fig. 2 is an enlarged fragmentary longitudinal sectional view of the same with the rolls transposed from the position of Fig. 1;

Fig. 3 is a plan elevation thereof with parts broken away;

Fig. 4 is a side elevation thereof, partly in section as on line 4-4, Fig. 3;

Fig. 5 is a fragmentary transverse sectional view as on line 5-5, Fig. 4;

Fig. 6 is a fragmentary transverse sectional view as on line 6-6, Fig. 4;

Fig. 7 is a fragmentary plan view partly in section of a modified form of the improved scrubbing and polishing apparatus;

Fig. 8 is a side elevation thereof, partly in section as on line 8-8, Fig. 7;

Fig. 9 is a fragmentary transverse sectional view as on line 9-9, Fig. 8; and

Fig. 10 is a fragmentary end elevational view as on line 10-10, Fig. 8 with parts broken away.

Similar numerals refer to similar parts throughout the drawings.

Referring to Fig. 1, the improved scrubbing and polishing apparatus is indicated diagrammatically at G and includes reciprocating rotary brushes 44 and 44' arranged for contact with the opposite faces of the strip S, and rubber or other suitable rollers 45 and 45' arranged to back up the strip in alignment with the brushes 44 and 44'.

Means controlled by the hand wheels 46, 46' for applying appropriate pressure to the brushes 44, 44', and means power driven by a suitable motor 47 for rotating and reciprocating the brushes will hereinafter be described in detail.

Included in combination with the scrubbing mechanism G is a squeegee or pressure device 48 having preferably rubber rolls, and adapted for aligning and tensioning the strip. As shown in Figs. 2 to 6, inclusive, a pressure device or squeegee 48 similar to or identical with the squeegee 48 may be embodied in the entrance end of the scrubbing apparatus, and the rolls 44 and 45 are shown in interchanged position with rolls 44' and 45', which obviously has no effect on the scrubbing action.

The squeegees 48 and 48' also perform the

function of controlling the film of solution on the strip entering or leaving the apparatus. If desired a drip pan 48a may be positioned under the squeegee at the entrance end for collecting squeegeed liquid and diverting it back to the previous treating apparatus.

The improved scrubbing apparatus shown in Figs. 2 to 6 inclusive, preferably includes a base 11 on which laterally spaced side frame members 12 are supported. Transverse frame members 13 span the side frame members at the ends thereof and are secured thereto by bolts 14.

The squeegees 48 and 48' each preferably include a fixed lower roll 15 and a vertically movable upper roll 16, both rolls being rubber covered as shown at 15' and 16' respectively. The roll shafts 17 of the lower rolls 15 are journaled at their ends in bearings 18 which are mounted in bearing supports 19 clamped by bolts 20 to vertically extending guide rods 21 spaced longitudinally of the apparatus. The rods 21 are preferably secured at their top and bottom ends in anchor members 22 attached to the side frame members by screws 23.

The roll shafts 24 of the upper squeegee rolls 16 are journaled at their ends in bearings 25 which are mounted in bearing supports 26, and the supports 26 are vertically slidable on the guide rods 21. Helical springs 27 encircle the guide rods between the bearing supports 19 and 26 for yieldingly supporting the upper rolls 16. Means for yieldingly pressing the upper rolls 16 downwardly to grip the strip S for tensioning the same preferably includes a pressure plate 28 slidable on the guide rods 21 and abutting helical springs 29 interposed between the plate and the bearing support 26.

Means for manually adjusting the pressure plates 28 vertically to yieldingly press the upper rolls 16 downwardly preferably includes screws 30 threaded through the upper anchor members 22 and journaled at their lower ends in the pressure plates 28. Hand wheels 31 may be provided on the upper ends of the screws 30 for manually turning the same.

Each brushing roll 44 with its back up roll 45 is positioned in the apparatus at or opposite slotted openings 32 in the side frame members 12, and the bearing supports for the rolls are preferably adjustably mounted on the side frame members at the edge portions of said openings.

The back up rolls 45 and 45' are preferably provided with rubber coverings 45a and 45'a respectively, which constitute resilient facings for the back up rolls, and the rolls are preferably hollow as shown and provided with roll shafts 45b and 45'b.

As best shown in Fig. 5 the ends of each roll shaft 45b and 45'b are journaled in bearings 33 and the bearings 33 are mounted in bearing supports 34. The bearing supports have diverging flange portions 35 (Figs. 2 and 3) which are provided at their outer ends with vertically extending bolt slots 36 through which bolts 37 are screwed into the edge portions 38 of the openings 32 in the side frame members.

Accordingly, the back up rolls can be adjusted in the side frame members with respect to the squeegee rolls 48 and 48' so that the strip S passes in slightly arcuate paths from the squeegee rolls 48' upwardly over the back up roll 45', then downwardly under the back up roll 45, and then upwardly to the squeegee rolls 48.

The roll shafts 39 of the brush rolls 44 and 44' project rearwardly from the brush rolls and

are preferably mounted for axial reciprocation in bearing supports 50 as best shown in Fig. 5. The bearing supports 50 preferably include a bearing sleeve 51 journaling the end of shaft 39 for axial sliding movement therein, and washers 52 may be provided around the shaft at the inner end of the sleeve 51 for providing a water seal for the bearing. As shown an oil wick 53 may be provided for lubricating the sleeve bearing, and a removable plug 54 is provided in the casing of the support 50 for giving access to the wick.

The bearing supports 50 have screw rods 55 non-rotatably secured at their lower ends to the bearing supports 50 and having their upper ends extending into worm gear housings 56 which extend across the openings 32 in the rear side frame members 12 and are bolted to the tops thereof by bolts 57.

The roll shafts 39 have front projecting portions 58 which extend into and are supported in housings indicated generally at 59 and enclosing mechanism for rotating and reciprocating the rolls. The housings 59 are located in the openings 32 of the front side frame members 12, and are preferably provided with flange portions 60 (Fig. 4) overlapping and slidably abutting the edge portions 38 of the side frame openings 32. The flange portions 60 are provided with vertically extending slots 61 through which bolts or screws 62 are inserted and screwed into the edge portions 38 of the front side frame member 12. Thus the housings 59 are vertically adjustable on the side frame members.

Adjusting screws 63 extend vertically upward from the housings 59 and have their lower ends non-rotatably secured in said housings. These adjusting screws extend at their upper ends into worm gear housings 64 which extend across the tops of the openings 32 in the front side frame member 12 and are secured thereto by bolts or screws 65.

Means for manually adjusting each brush roll vertically preferably includes a horizontal worm shaft 65a extending between the side frame members and through the worm gear housing 64 and the worm gear housing 56, there being preferably a sleeve housing 66 enclosing the shaft 65a and connecting the gear housings 64 and 56. The front ends of the shafts 65a project outwardly from the housings 64 and are provided with hand wheels 46, 46' thereon. Within each housing 64 the worm shaft 65a is provided with a worm 68 meshing with a worm gear 69 which is keyed on a sleeve nut 70 in which the screw 63 is threaded. Likewise, within the housing 56 the worm shaft 65a is provided with a worm 71 which meshes with a worm gear 72 keyed on a sleeve nut 73 in which the adjusting screw 55 is threaded.

Thus by loosening the screws 62 which clamp the housing 59 to the side frame, and then turning the hand wheels 46, 46' the brush rolls may be adjusted vertically with respect to the back up rolls. As shown in Fig. 2, the brush rolls are positioned to brush or sweep lightly over the slightly convex arcuate portions of the strip at the points where the strip passes over the back up rolls, the brush roll 44' contacting the upper convex arcuate surface of the strip at the back up roll 45' and the brush roll 44 contacting the lower convex arcuate surface of the strip at the brush roll 45.

When used for brushing or scrubbing the rolls 44, 44' may have fiber or wire bristles, when used

for polishing the bristles may be replaced or covered by felt and the like, and when used for burnishing the brush rolls may be covered with metallic wool facings.

As shown in Fig. 4 the housing 59 in which brush roll 44' is journalized is at the upper limit of its adjustment on the side frame member 12, so that the brush roll 44' can be adjusted downwardly as the brush bristles wear to maintain a constant line of brushing contact with the strip, and the housing 59 in which the brush roll 44 is journalized is at the lower limit of its adjustment so that as the bristles of said brush roll wear, it can be adjusted upwardly to maintain the desired line of brushing contact with the strip.

As shown in Figs. 2, 3, 4, 5, 7, 8 and 9, the diameters of the back up rolls in the preferred arrangement are approximately the same as the diameters of the brush rolls, when the brush rolls are new. In these figures of the drawings, the brush rolls are shown as being new and at their outer limit of adjustment relative to the back up rolls, and as the brush bristles wear, the diameters of the brush rolls become smaller, so that the diameters of the back up rolls become relatively larger with respect to the brush rolls. However, the back up rolls may be approximately three-fourths the size of the brush rolls in diameter when the brush rolls are new, as shown in Fig. 1, which corresponds to Fig. 5 of my parent application Serial No. 133,911 (Patent No. 2,240,265), or the back-up rolls may initially be approximately two-thirds of the size of the brush rolls in diameter, as shown in Fig. 11 of said Patent No. 2,240,265.

Accordingly, the back up rolls have a diameter in the order of about two-thirds of the diameter of the brush rolls, although the exact relationship may vary due to the wear in the brush rolls. The expression that the back-up rolls have "a diameter in the order of the diameter of the brush rolls" as used herein and in the claims, is intended to define a back up roll and brush roll diameter relationship of the order of those illustrated and described.

Suitable means (not shown) may be provided for differentially adjusting the back up rolls when the clamping bolts 37 are loosened so as to make the outer periphery of the back up roll accurately conform to the outer periphery of the bristles of the brush roll at all times, so that the line of contact of each of the back up rolls 45' and 45 with the strip S is always parallel with the line of contact of the brush rolls 44' and 44 respectively, with the strip.

The means for driving the brush rolls 44 and 44' preferably includes a drive shaft 75 (Fig. 4) mounted on the base 11 at the front side of the apparatus and operatively connected at one end with the motor 47 by means of suitable gearing 76. The shaft 75 has secured thereon a bevel gear 77 meshing with the bevel gear 78 connected to a collar 79 in which the vertical shaft 80 is splined, and the shaft 80 drives the brush roll 44. In a similar fashion the shaft 75 has a bevel gear 81 thereon meshing with a bevel gear 82 secured to a collar 83 in which a vertical shaft 84 is splined, and the shaft 84 drives the brush roll 44'. The spline connection between the shafts 80 and 84 and the collars 79 and 83 respectively, provides a slid able driving connection which permits adjustment of the housings 59 in which the brush roll shafts are journalized.

Each of the shafts 80 and 84 has a worm gear

85 thereon which meshes with a pinion 86 secured to or integral with a driving sleeve 87 which encircles the projecting end 58 of the brush shaft 39. The driving sleeve 87 has a splined connection indicated at 88 with the end of shaft 39 so as to permit axial reciprocation of the shaft 39 while being driven by the sleeve 87. As shown, the sleeve 87 may be journaled in the housing 59 by suitable bearings 89, and gaskets 90 may be provided around the projecting portion 58 of the shaft at the inner side of the housing for providing a water seal for the housing 59 adjacent to the brush roll.

The means for laterally reciprocating the brush rolls preferably includes a pinion 91 keyed on the driving sleeve 87 and meshed with a gear 92 secured on a worm shaft 93 journaled in the housing 59 below the driving sleeve 87. A worm 94 on the worm shaft 93 meshes with a worm gear 95 journaled in bearing brackets 96 mounted on the bottom wall 97 of the housing 59. The worm gear 95 is provided with crank arms 98 to which links 99 are pivotally connected at one end, and the other ends of links 99 are pivotally connected as at 100 to the arms 101 of a yoke straddling the end portion 102 of the shaft roll 39 and pivotally mounted on a rocker shaft 103 secured in the upper end of housing 59.

The end 102 of shaft 39 is axially slidible in a sleeve bearing 104 provided in the housing 59, and a bearing collar 105 encircles the shaft within the yoke and is provided with side projections 106 secured to the arms 101 of the yoke. The bearing collar 105 houses an anti-friction bearing for the end portion 102 of shaft 39, and the bearing collar is also provided with upper and lower projections 107 providing guide ways for guide bars 108 secured to the front wall of the housing 59 as by screws 109.

Thus as the brush shafts 39 are rotated by the vertical shafts 80 and 84 operatively connected to the pinions 86 on the driving sleeves 87, the pinions 91 on the driving sleeves 87 will drive the worm gears 95 and oscillate the side bars 101 of the yoke, and the movement of the yoke will reciprocate the bearing collar 105 and with it the brush roll shaft 39, with the result that the brush shafts reciprocate laterally of the strip while they are rotating. The reciprocation of the brush rolls while rotating provides for imparting a uniform scrubbing action over the surface of the strip and greatly aids in eliminating scratches or other marking on the surface of the strip.

Spray pipes 110 are provided above and below the path of the strip S at opposite sides of each brush roll 44', 44 and the back up rolls 45' and 45 therefor, for spraying water or other cleansing fluid on the strip as it passes between the brush rolls and back up rolls.

The spray pipes 110 extend parallel to the brush rolls and back up rolls and may be connected at one end to a suitable source of liquid supply (not shown).

In the modified form of improved scrubbing and polishing apparatus shown in Figs. 7 to 10 inclusive, the frame preferably includes laterally spaced upright members 11c at intervals longitudinally of the apparatus, and each member 11c may comprise a channel 12c and a plate 13c secured across the legs thereof with supporting angles or feet 14c secured to the base.

A series of brush rolls 44'c and 44c with vertically aligned back up rolls 45'c and 45c are journaled between the frame members, each

brush roll and its back up roll being located opposite the opening formed between a pair of adjacent frame members 11c. The brush rolls and back up rolls are preferably staggered with respect to the strip S' passing through the apparatus, that is, alternate brush rolls and alternate back up rolls are located above and below the strip so as to uniformly scrub both surfaces thereof.

10 A pressure device or squeegee is preferably located at the discharge end of the apparatus and includes a fixed upper roll 16c and a vertically movable lower roll 15c, both of which rolls may be rubber covered as desired.

15 The roll shaft 17c of the lower roll 15c is journaled at its ends in bearings 18c which are supported on lever arms 19c hinged at their inner ends as at 20c on brackets 21c secured to the end frame members 11c. The lever arms 19c are yieldingly held in position by means of rods 22c passing through their outer ends, with springs 23c interposed between the lever arms 19c and nuts on the rods above and below the same. At their lower ends the rods 22c are 25 pivoted to links 24c which are in turn pivotally connected with a suitable adjusting device 25c.

The roll shaft 26c of the upper roll 16c is journaled at one end in a bearing 27c mounted on a suitable bracket 28c secured to the frame, 30 and at its other end in a bearing 29c supported on a bracket 30c secured to the frame, the shaft 26c extending through the bearing 29c for driving connection with a suitable motor 31c for driving the squeegee roll 16c independently.

35 The roll shafts 32c of the upper brush rolls 44c are journaled at their ends in bearings 33c which are carried by laterally extending arcuate shield members 34c positioned around the upper portions of the brush rolls and projecting laterally beyond the frame members 11c at each side thereof. Similarly the lower brush rolls 44c have their roll shafts 32c journaled at their ends in bearings 33c which are carried by laterally extending arcuate members 34c positioned around the lower portions of the brush rolls 44c and extending laterally beyond the frame members 11c at opposite sides thereof.

The arcuate members 34c for the upper brush rolls 44c are supported at each end for lateral movement in vertically movable end frames 35c which are slidably mounted in ways 36c on the frame members 11c, and the arcuate members 34c for the lower brush rolls 44c are supported at each end for lateral movement in vertically movable end frames 35c slidably mounted in ways 36c on the frame members 11c.

60 The roll shafts 32c and 32c of the upper and lower brush rolls are extended at one side of the apparatus for operative connection with individual brush roll driving motors 37c and 37c respectively, which motors are suitably supported on laterally extending plates 38c and 38c secured at their inner ends to the arcuate members 34c and 34c respectively.

65 Means for vertically adjusting the upper brush rolls 44c preferably includes screws 39c screwed in the end frames 35c and having worm gears 40c on their upper ends meshed with worms 41c on the shafts 42c which are manually rotatable by means of hand wheels 43c. The lower brush rolls 44c are similarly adjusted by hand wheels 43c on worm shafts 42c for turning screws 39c. As shown in Fig. 8, the screws 39c are connected to the end frames 35c by spaced arms 46c

which straddle the roll shafts of the upper back up rolls 45c.

The upper arcuate members 34c preferably have lugs 47c projecting therefrom engaging rollers 48c journaled at opposite sides of the end frames 35c for permitting lateral movement of the arcuate members in the end frames, and similarly, the lower arcuate members have lugs 47c projecting therefrom engaging rollers 48c journaled at opposite sides of the end frames 35c.

Preferably the roll shafts 49c and 49c for the upper and lower back up rolls have their ends journaled in stationary bearings mounted on angle or channel members 50c extending between adjacent frame members 11c, and at one side of the apparatus, the back up roll shafts are extended for operative connection with individual back up roll driving motors 51c and 51c supported on suitable brackets 52c carried on the frame members 11c.

Means for laterally reciprocating the brush rolls preferably includes an oscillating shaft 53c journaled in bearing brackets 54c on the frame members 11c and extending longitudinally of the apparatus between the brush roll shafts 32c and 32c. The shaft 53c is driven by a separate motor 55c supported on a suitable bracket 56c carried on the frame members 11c.

The motor 55c drives a crank having a link 57c pivoted thereto at one end and the other end of the link is pivoted to an arm 58c having its other end secured to the shaft 53c for oscillating the same. Lever arms 59c are secured on the shaft 53c and link-connected to lugs 60c depending from the upper brush roll arcuate members 34c, and similar lever arms 61c are secured on the shaft 53c and link-connected to lugs 62c projecting upwardly from the lower brush roll arcuate members 34c.

Accordingly, when the shaft 53c is oscillated the upper arcuate members 34c and lower arcuate members 34c and the brush rolls carried thereby will be reciprocated laterally of the strip S', the upper brush rolls moving in one direction while the lower brush rolls are moving in the opposite direction, and vice versa, to impart a uniform scrubbing action to both surfaces of the strip.

As shown, spray pipes 63c may be provided above and below the strip adjacent to and parallel with the brush rolls and back up rolls, for spraying water or other cleansing liquid on the strip as it passes between the brush rolls and back up rolls. Preferably a closed liquid tank having sheet metal walls indicated at 64c is provided for enclosing the brush rolls and back up rolls, and said tank may have a drain 65c.

In the modified form of the invention, the brush rolls can be reciprocated or not, as desired, by independently operating the motor 55c which drives the oscillating shaft 53c.

Reciprocation of the brush rolls is desirable when brushing or polishing multiple strips of heavy gauge because otherwise there is a tendency to wear grooves in the face of the brush roll which requires very frequent trimming of the bristles.

On the other hand, reciprocation of the brush rolls may not be desirable where the strips are of light gauge and are brushed under low tension, because the strips would reciprocate with the brushes and there is a tendency to curl the edges and scratch the surface which is against the back up roll.

When brushing or polishing wide material at 75

slow strip speeds, reciprocation of the brush rolls tends to cover up or prevent streaking on the strip surface which might be caused by a brush roll not in perfect trim. However, at relatively high strip speeds, the brush reciprocation will not cover up streaking but will merely form a wavy streaking, and under these conditions the brushes must be kept in perfect trim to get perfect polishing, whether reciprocated or not.

With the present invention, the brush rolls are easily and inexpensively maintained in perfect trim, so as to insure perfect scrubbing or polishing under all conditions.

The present invention provides a novel and improved apparatus for rapidly and inexpensively scrubbing, brushing, polishing or burnishing strip material of various kinds under varying conditions, to produce a uniform surface on the strip without scratches, streaks or stains, and without causing undue wear on the bristles of the brush rolls.

I claim:

1. Scrubbing and polishing apparatus including a frame, a brush roll journaled in said frame, a back up roll journaled in said frame in vertical alignment with said brush roll, means for passing a strip between said rolls so as to present a convex arcuate surface of the strip to said brush roll, means for adjusting said brush roll toward and away from said strip, means for reciprocating said brush roll transversely of said strip, and means for rotating the reciprocable adjustable brush roll.

2. Scrubbing and polishing apparatus including means for supporting a continuously moving strip and maintaining portions thereof in slightly arcuate form, brush rolls for brushing under pressure the convex surfaces of said arcuate portions alternately on opposite sides of the strip, and means driven from said brush rolls for reciprocating said brush rolls transversely of said strip.

3. Scrubbing and polishing apparatus including means for supporting a continuously moving strip and maintaining portions thereof in slightly arcuate form, brush rolls for brushing under pressure the convex surfaces of said arcuate portions alternately on opposite sides of the strip, means for adjusting said brush rolls toward and away from said strip, means for rotating said brush rolls, means for reciprocating said brush rolls transversely of said strip, and means driven by the rotating brush rolls for operating the reciprocating means.

4. Scrubbing and polishing apparatus including means for moving a continuous strip under tension through said apparatus, brush rolls arranged alternately above and below said strip, back up rolls arranged alternately above and below said strip in vertical alignment with said brush rolls, said back up rolls being positioned to maintain the portions of the strip passing thereover in slightly arcuate form, means for adjusting said brush rolls toward and away from said strip for brushing under pressure the convex surfaces of said arcuate portions, means for rotating said brush rolls, means for reciprocating said brush rolls transversely of said strip, and means driven by the rotating brush rolls for operating the reciprocating means.

5. Scrubbing and polishing apparatus including a frame having vertical slots therein, tensioning rolls journaled in one end of said frame for moving a continuous strip through said ap-

paratus; brush rolls arranged alternately above and below said strip, bearing supports having housings journaling the ends of said brush rolls and adjustably mounted in said frame slots, back up rolls journaled in the frame and arranged alternately above and below the strip in vertical alignment with said brush rolls, said back up rolls being positioned to maintain the portions of the strip passing thereover in slightly arcuate form, means for adjusting said bearing support housings for moving said brush rolls toward said strip to contact the convex surfaces of said arcuate portions, means including gearing and shafts within the bearing support housings and movable therewith at one end of said brush rolls for rotating said brush rolls, and drive means fixed relative to the frame for driving the brush rolls in all positions of adjustment.

6. Scrubbing and polishing apparatus including a frame having vertical slots therein, tensioning rolls journaled in one end of said frame for moving a continuous strip through said apparatus, brush rolls journaled in the frame and arranged alternately above and below said strip, back up rolls journaled in the frame and arranged alternately above and below the strip in vertical alignment with said brush rolls, said back up rolls being positioned to maintain the portions of the strip passing thereover in slightly arcuate form, bearing supports having housings journaling the ends of the brush rolls and adjustably mounted in said frame slots, means for adjusting said housings for moving said brush rolls toward said strip to contact the convex surfaces of said arcuate portions, means for rotating each of said brush rolls, and means driven by each of said brush rolls for reciprocating the brush rolls transversely of the strip while they are rotating, the brush roll rotating means and the reciprocating means being both mounted and enclosed in the bearing support housings at one end of the brush rolls.

7. Scrubbing and polishing apparatus including a frame, tensioning rolls journaled in one end of said frame for moving a continuous strip through said apparatus, brush rolls journaled in the frame and arranged alternately above and below said strip, back up rolls journaled in the frame and arranged alternately above and below said strip in vertical alignment with said brush rolls, said back up rolls being positioned to maintain the portions of the strip passing thereover in slightly arcuate form, means for adjusting said brush rolls toward said strip for contacting the convex surfaces of said arcuate portions, means for rotating said brush rolls, and independent means for rotating said back up rolls.

8. Scrubbing and polishing apparatus including a frame, a brush roll having a shaft journaled in said frame, a back up roll journaled in said frame in vertical alignment with said brush roll, means for passing a strip continuously be-

tween said rolls so as to present a convex arcuate surface of the strip to said brush roll, a driving sleeve secured on said brush roll shaft, means for driving said driving sleeve for rotating said brush roll, and means driven by said driving sleeve for reciprocating the brush roll while the same is rotating.

9. Scrubbing and polishing apparatus including a frame, tensioning means for moving a continuous metal strip through said apparatus, brush rolls journaled in the frame and arranged alternately above and below said strip, back up rolls having a diameter in the order of the diameter of the brush rolls to permit the tensioned metal strip to conform to the back up roll surfaces without causing permanent distortion of the metal strip, said back up rolls being journaled in the frame and located alternately above and below said strip and maintained in vertical alignment with said brush rolls, said back up rolls having resilient facings and being positioned to maintain the portions of the tensioned strip passing thereover backed up in slightly arcuate form, means for adjusting said brush rolls relative to said strip for contacting the brush rolls with the tensioned convex surfaces of said arcuate portions and for maintaining the desired pressure between the brush rolls and the backed up arcuate strip portions independently of the tension on the strip, means for rotating said brush rolls, and means for spraying liquid on the tensioned moving strip as it passes between the brush rolls and back up rolls.

10. Scrubbing and polishing apparatus including a frame, cylindrical back up rolls journaled in the frame for guiding a continuous metal strip, means for moving said continuous strip under tension in a sinuous path alternately under one and over another of said back up rolls to cause each portion of the strip to conform with the shape of each back up roll momentarily and to present a tensioned convex arcuate surface, said back up rolls having a diameter in the order of the diameter of the brush rolls to permit the tensioned metal strip to conform to the back up roll surface without causing permanent distortion of the metal strip, brush rolls journaled in said frame in position to contact the convex arcuate surfaces of the continuous tensioned metal strip as it passes in said sinuous path, means for adjusting the distance between each back up roll and its associated brush roll for varying the pressure between the brush roll and the arcuate surface of the strip independently of the strip tension, means for maintaining the axis of rotation of each brush roll and its associated back up roll in parallel relationship at right angles to the path of strip travel and for maintaining the lines of contact of the brush and back up rolls with the strip always parallel, and means for rotating the brush rolls.

JOHN S. NACHTMAN.
